UNITED STATES PATENT OFFICE.

ALFRED HORATIO HUMPHREY, OF SALEM, NEW YORK, ASSIGNOR TO GRACE G. HUMPHREY, OF SALEM, NEW YORK.

SIGN.

Application filed October 22, 1924. Serial No. 745,202.

My invention relates to a sign and particularly to a highway sign mounted on a post and having a plurality of illuminated sides as for example at the intersection of 5 roadways.

The general object of my invention is to provide an illuminated sign in which a minimum number of lights will afford the maximum diffused illumination at the several 10 sides of the sign, and to provide ample interior illumination for the desirable visibility of the sign from the front or at an angle and without the necessity of employing the usual external illumination.

15 A further object of the invention is to provide a sign of the indicated character embodying a frame of few parts and of simple form and of a character to possess the maximum strength and stability.

20 Specifically, the invention has for an object to provide a sign in which the lighting means is made readily accessible.

25 The nature of my invention and its distinguishing features and advantages will clearly appear as the description proceeds.

Reference is to be had to the accompanying drawings forming a part of this specification, it being understood that the drawings are merely illustrative of one example 30 of the invention.

Figure 1 is a vertical section of a sign embodying my invention, a part of the post and central tube therein being broken away;

35 Figure 2 is a horizontal section in the plane indicated in the line 2—2, Figure 1;

Figure 3 is an elevation of the reflector assemblage at each side of the sign;

Figure 4 is a perspective view of the skeleton frame of the sign;

40 Figure 5 is a fragmentary view in elevation showing the light-emitting openings in a form to constitute letters.

In carrying out my invention in practice a post 10 usually of concrete is provided, to be set up at any desired point along a highway. The sign supported on the post 10 at the upper end comprises central vertical elements 11 arranged in box-like form to accommodate at the lower portion of the sign 45 the upper end of the post 10. At two opposite sides of the central assemblage of upright frame members 11 are side frames designated generally by the numeral 12 composed of a top frame 13, a bottom frame 14,

and upright frames 15 at the front of each side frame 12. The top and bottom frames 13, 14 flare from the back forwardly to the front, and the back of each frame 13, 14 is secured to a pair of the upright frame member 11 below the upper ends of said members 11. The members 13, 14, 15 are in one piece which is notched at the corners to facilitate bending.

To each side frame 12 and between the ends of said frames 12, I provide reflectors so that there is a reflecting assemblage provided for each side of the sign, the illustrated sign being four-sided. The reflectors include flat side reflecting plates 17 convergent toward the inner end and extending obliquely from a member 15 or corner of the side frame 12 to the vertical frame members 11. In association with the pair of side plates 17, I employ a central reflecting plate 18 curved vertically, that is, from the bottom edge, to the top edge, and the sides of said plate are concave in the arc of a circle so that at the bottom edge and the top edge of the reflecting plate 18; said plate extends laterally to the vertical corner members 15 while at the center or waist of the plate 18, the curvature of the same disposes the central narrow portion against the outer faces of the vertical frame members 11. Thus, at 55 each side of the central frame assemblage formed by the vertical members 11, there is a curved reflector plate 18 and at both sides of the curved reflector plate 18 there are flat reflector plates 17 convergent from the front 60 to the sign inwardly toward the center.

I would mention that the reflecting character of the plates 17 and 18 may be produced by white paint or the side plates 17 may be painted white or enameled white, and the central curved reflector may be either painted white or mirrored. Side plates 17 reflect at both sides; thus one side plate reflects in two compartments. In each central plate 18 at the narrow portion is a hole 19 through which holes pass the lateral tubular arms 20 carrying lighting means. Said arms are appurtenant to a tube 23 which may be a gas pipe or conduit for electric wires. In the illustrated example the arms 20 are equipped with sockets 21 for electric lamps 22.

100 I make provision in my improved sign for affording access to the lighting means through the reflector plates 18 from the cen- 105

ter of the sign, that is to say, within the frame assemblage formed by the members 11. Each reflector plate 18 is formed with an opening equipped with a closure 24 disposed at the back of said reflector plate 18, that is, toward the central frame assemblage formed by members 11 and each closure 24 opens toward the interior of said assemblage.

At the upper end of the frame assemblage formed by the vertical members 11 is a horizontal top frame 26. Fitting the top frame 26 is a base 27 of an ornament 28 which may be of any design or character, illuminated or otherwise. Said ornament 28 in the illustrated example is in the form of a ball. The engagement of the base 27 with the frame 26 is a detachable one so that with a lifting off of the ornament 28 and its base 27, an arm may be passed downwardly with 20 in the frame members forming the assemblage 11 and laterally between the same to open a given closure 24 to afford access to the lighting means 21, 22.

A suitable roof or cap 29 is provided advantageously a roof tapering upwardly at all sides and overlapped by a flange 127 on the base 27. Each side of the sign is closed by a suitable closure or front 30 here shown as in the form of a flat plate and herein-after termed the front and said front 30 is formed with light-emitting-apertures 31 as shown in Figures 1 and 2. The light-emitting apertures in the front designated 130 in Figure 5 may be arranged in the form of sign letters 131. The numeral 115 represents holes in the upright members 15 in the side members 12 for fastening the plates 17, 18. The numeral 25 indicates drainage apertures in the front pairs of the bottom frames 14 so that if any water should find entrance through the openings 21 or otherwise to the interior of the sign, such water or moisture will drain through the apertures 25.

In order that the light reflected by the plates 17, 18 may be diffused and cause an ample illumination, the front end of each lamp 22 is painted as indicated at 122 to make the same opaque and prevent illumination by direct forward rays.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a sign structure, an elongated vertical frame and a side frame connected thereto, a sign at the front of the side frame, said elongated frame affording accommodation for the upper end of a supporting post and

extending materially above the post end, reflector means disposed at the same side of the elongated frame as said side frame and connected therewith and presenting an opening at the back thereof and a closure therefore, and lighting means positioned adjacent said opening, said elongated frame affording access therethrough and through the opening in the reflector to said lighting means.

2. In a sign structure, a central frame assemblage, side frames spaced from each other and connected to said central frame assemblage, signs at the sides of said structure and reflector means supported in said side frames and between said side frames, said reflector means at each side of the sign comprising flat side reflector plates and a central vertically curved reflector plate, together with means in front of said reflector means adapted to receive and support light-producing means.

3. In a sign structure, an elongated central supporting frame, side frames connected to said central frame, and projecting outwardly therefrom, a sign at the front of said side frames, and reflector means in said side frames, said reflector means including a pair of inwardly convergent side plates and a vertically curved reflector plate between the inner ends of the convergent plates, together with means in front of said reflector means adapted to support light producing means.

4. In a sign structure, an elongated central supporting frame, side frames connected to said central frame and projecting outwardly therefrom, a sign at the front of said side frames, and reflector means with said side frames, said reflector means including a pair of inwardly convergent side plates and a vertically curved reflector plate between the inner ends of said convergent plates, said curved reflector plate having concave side edges, together with means in front of said reflector plates adapted to support light producing means.

5. In a sign structure a vertically disposed central supporting frame assemblage, affording accommodation for the upper end of a supporting post and extending materially above said post end, signs at the sides of said structure, reflector means disposed at opposite sides of said central frame assemblage and presenting an opening at the back thereof, and a closure for said opening, together with lighting means positioned adjacent said opening, said central frame assemblage affording at the interior thereof access through said openings in the reflectors to said lighting means.

6. In a sign structure, a central frame and side frames, said central frame affording accommodation for the upper end of supporting post, reflector means grouped around the central frame, signs at the sides of said

structure, and opposite the reflector means, lighting means adjacent the reflector means, a tube extending vertically through the aforesaid support post, and lateral tubular 5 arms on said tube, said arms extending through the reflector means to the front thereof and supporting said lighting means.

7. In a sign structure, a frame including an elongated vertically disposed assemblage 10 of members at the approximate center, reflector means at the sides of the frame, said reflector means including side plates convergent laterally and inwardly and a vertically curved reflector plate between the inner ends of said side plates, said side plates 15 presenting reflecting surfaces on their two faces, together with means in front of said

reflector means adapted to support light producing means.

8. In a sign structure an elongated vertical frame, a side frame connected to said elongated frame, a sign at the front of the side frame, said elongated and side frames presenting openings at the back of said sign, reflector means in said side frame, the rear side and rear reflector provided with an opening, means adjacent said reflector opening to receive and support lighting means, a closure for said reflector opening, said closure movable to afford access to the lighting means through the openings of the elongated and side frames. 20 25 30

ALFRED HORATIO HUMPHREY.
